UNITED STATES PATENT OFFICE.

ELIJAH FRAZIER AND NATHAN J. EDWARDS, OF WINCHESTER, INDIANA.

POST AND WELL AUGER.

SPECIFICATION forming part of Letters Patent No. 284,956, dated September 11, 1883.

Application filed April 17, 1882. (No model.)

To all whom it may concern:

Be it known that we, ELIJAH FRAZIER and NATHAN J. EDWARDS, of Winchester, Randolph county, and State of Indiana, have invented certain Improvements in Post and Well Augers, of which the following is a specification.

Our invention relates to that class of earth-augers which are provided with two bent blades joined together by means of a cross-arm having a shaft, to which a handle is attached. These blades were formed of a thin plate of metal having a triangular form, the equal sides being arcs of a circle having equal radii, and the body on their inner sides concaved equally from the median longitudinal line to the equal sides, and secured together in such a manner that the equal edges of one blade were overlapped at one side and underlapped at the other side by the other blade. Augers made in this way must be constantly forced into the earth by downward pressure exerted upon the handle.

The object of our invention is to obviate the necessity for this downward pressure, so that the whole strength of the operator may be used in turning the device.

To this end the nature of our invention consists of an earth-auger of the kind described, having its blades bent in such a manner that they form a hollow screw, which, as the handle is turned, will, from its peculiar shape, force its way in the ground, all as will herein-after be described and claimed.

Referring to the drawings, in which like letters of reference indicate the same part, Figure 1 is a side elevation of the tool; Fig. 2, an elevation of the outside of the blade; Fig. 3, an elevation of the inside of the blade, and Fig. 4 a top plan of one of the blades.

A represents the blades, B the yoke, C the stem, and D the handle, all of which, except the former, are substantially the same as those

in the ordinary device, and further description of them seems unnecessary. The yoke B is attached to one side of the median line xx upon a substantially flat surface, a . The side a' of the plates is curved abruptly inwardly from the top a^2 to a point, a^3 , on the side a . From the point a^3 to the point a^6 an inward swell, a^4 , is given to the curve, so as to project the point a^7 toward the median line yy of the augers. The swell a^4 is directly opposite the flat surface a , and the points a^3 are in the same vertical plane as the yoke B. The inner part, a^8 , of the blade and cutting-edge, between the points a^3 and a^6 , is depressed to form a continuation of the groove formed by the swell a^4 , so that the dirt, in ascending, will clear the yoke B. The curve gives the blade a screw-like formation, and, when the auger is turned, draws the blades downward and forces the cut dirt upwardly between the blades.

What we claim as new is—

1. In an earth-auger, cutting-blades having the points a^6 opposite each other and in the same vertical plane as the yoke B, and the side a' , curved inwardly from the top a^2 to a point, a^3 , to form a groove, substantially as described.

2. In an earth-auger, cutting-blades having a flat and curved part, the flat part of each blade being opposite the curved part of the other blade, and the curved part approaching the median line yy .

3. In an earth-auger, the blade A, having flat side a , side a' , curved inwardly from the top a^2 to a point, a^3 , inward swell a^4 , depressed part a^8 , forming a continuation of the swell a^4 , and the point a^5 , substantially as described.

ELIJAH FRAZIER.
NATHAN J. EDWARDS.
